HOUSING FIXTURE FOR ODOR-OXIDIZING OZONE LAMP

Clyde D. McCann, Des Moines, Iowa

Application February 23, 1952, Serial No. 18,643

Term of patent 14 years

(Cl. D48—4)

To all whom it may concern:

Be it known that I, Clyde D. McCann, a citizen of the United States, residing at Des Moines, in the county of Polk and State of Iowa, have invented a new, original, and ornamental Design for a Housing Fixture for Odor-Oxidizing Ozone Lamp, of which the following is a specification, reference being had to the accompanying drawing, forming a part thereof.

Fig. 1 is a front view of a housing fixture for odor-oxidizing lamp, showing my new design.

Fig. 2 is a side view of this housing fixture, and Fig. 3 is a top plan view of the same.

I claim:

The ornamental design for a housing fixture for odor-oxidizing ozone lamp, substantially as shown.

CLYDE D. McCANN.
